UNITED STATES PATENT OFFICE.

CARROLL KNOWLES, OF HARTFORD, CONNECTICUT, ASSIGNOR TO PRATT & WHITNEY COMPANY, OF NEW YORK, N. Y., A CORPORATION OF NEW JERSEY.

MULTIPLE-CYLINDER GRINDER.

Application filed March 18, 1925. Serial No. 16,343.

This invention relates to grinding machines and particularly to an internal grinding machine for simultaneously grinding the bores of an automobile engine cylinder.

5 It is an object of the invention to provide a table on which may be carried an engine body to be ground, and to provide improved means for actuating the table bodily in a planetary path so that each of the cylinder 10 bores may be simultaneously engaged by its grinding wheel.

One feature which is advantageous is that I provide two adjustable or compound eccentrics, the radius of throw of which may be simultaneously varied, these eccentrics being located one in the forward part of the table and the other one toward the rear so that a line connecting the eccentrics extends 20 in a direction normal to the line of the cylinders being ground.

Another object of the invention is to provide an improved form of mounting for one 25 of the eccentrics relative to the table so that it may be permitted to adjust itself within an elongated slot in the table.

With these and other objects in view, my invention consists in the features of construction and operation set forth in the following specification and illustrated in the 30 accompanying drawings.

In the accompanying drawings annexed hereto and forming a part of this specification, I have shown my invention embodied in a machine for simultaneously grinding 35 all of the cylinder bores of an automobile engine, but it will be understood that the invention can be embodied in different machines and that the drawings are not to be construed as defining or limiting the scope of the invention, the claims appended to this specification being relied upon for that purpose.

In the drawings:

Figure 1 is a side elevation of the complete grinding machine, parts being broken away to more clearly disclose their construction.

Fig. 2 is a front elevation of the complete machine.

Fig. 3 is a plan view of the work supporting table and actuating means therefor, the housings and spindle supports being removed, and

Fig. 4 is a detail view of the rear eccentric 55 and its mounting relative to the table.

In the above mentioned drawings I have shown but one embodiment of the invention which is now deemed preferable, but it is to be understood that changes and modifications may be made within the scope of the appended claims without departing from the spirit of the invention.

Briefly and in its broadest aspect, my invention comprises the following principal parts: first, a base; second, a work supporting table or platen movable upon an upper surface of the base; third, actuating means for bodily moving the table in planetary paths of different radii; fourth, grinding wheels for each of the cylinder bores; and fifth, means to support, traverse and rotate these wheels during the movement of the table.

Referring more in detail to the figures of the drawings, I provide a base 10, on which 75 may be mounted a table 11. This table 11 is adapted to move about upon a plane horizontal surface formed on the base 10. Preferably, and as shown in Fig. 3, the table 11 is provided with a rearward integral extension 12 and its forward portion is widened sufficiently to properly mount and support an automobile engine cylinder body.

Supported on the base 10, upon opposite sides of the rear, are columns or housings 13 85 on which is movably mounted a cross rail 14. On this cross rail 14 are wheel heads 15 which may be adjusted along the rail 14 and clamped securely in position thereon. Each head 15 is provided with a spindle 16 rotatably mounted within its head and provided at its lower end with a grinding wheel 17. A pulley 18 splined to the upper ends of the spindles 16 provides means for rotating it as by means of belts 19 extending over a plurality of pulleys 20 mounted on a shaft 21 95 on the columns 13. This shaft 21 may, as shown in Fig. 2, be driven from a main driving pulley 22.

In order to raise and lower the grinding 100 wheels 17 simultaneously during operation, screws 25 are provided, the said screws being held against end-wise movement and supported upon the forward surfaces of the columns 13. By rotating these screws 25 in 105 opposite directions by any preferred means, the cross rail 14 and abrasive wheels 17 may be raised or lowered to properly engage them with the full length of the cylinder bores on the work W. In order to rotate 110

these screws 25 a gear box 26 is provided on one of the columns 13 having a driving shaft 27 extending therefrom to any suitable source of power. As the invention does not relate to any specific form of wheel actuating or rotating mechanisms, it is not thought that further description of these parts will be necessary.

In order to actuate the table 11 in a planetary path to simultaneously engage each of the grinding wheels 17 respectively with the surfaces of the different bores of the cylinder body W, two eccentrics 30 and 31 are provided each of the compound type, so that their throw or eccentricity may be widely varied. It will be understood that the movement of the table in its planetary path causes the wheels to engage the entire circumference of the different bores of the cylinders. Also this planetary movement must vary for cylinders of different diameters and to compensate for the wheels being gradually reduced in size by wear. The eccentrics are therefore designed so that they may be adjusted to vary this planetary movement of the table over wide limits. For convenience the eccentrics are designed for simultaneous adjustment during operation and in all positions of adjustment the eccentricity or throw of the members in engagement with the table is always precisely equal. These eccentrics, as shown clearly in Figs. 1 and 2, comprise shafts 32, the upper ends 30 and 31 of which form the parts engaging the table 11. The shafts 32 are mounted eccentrically within sleeves 33 as shown in Fig. 1. The forward eccentric 30 is retained within a bored hole in the table preferably provided with a bushing 34 with in which the extension 30 is free to rotate. The rear eccentric 31 is preferably freely rotatable within a block 35 slidably mounted in an elongated opening 36 provided in the table 11. Except for this manner of connecting the eccentrics 30 and 31 with the table 11 the construction of the assembled eccentrics is identical. A description of one of the compound eccentrics will therefore suffice for both.

50 To angularly position the eccentric sleeve 33 relative to the second eccentric sleeve 39 surrounding it to vary the eccentricity of the shaft 32 and its extension 30 or 31, two worm wheels 37 and 38 are provided for each eccentric. One worm wheel 38 is adapted to rotate the sleeve 33 within the second eccentric sleeve 39 and a second worm wheel 37 is adapted to directly engage the outer sleeve 39. It will be seen that if these worm wheels 37 and 38 are rotated relatively to each other the angular position of the eccentric sleeve 33 will be changed relative to the eccentric sleeve 39 and the amount of eccentricity of the eccentric 30 or 31 will be changed relative to the axis about which the

bearing member 39 rotates. The eccentricity of the eccentrics 30 or 31 which directly engage the table 11 relative to their axes of rotation is therefore widely varied by simply varying the relative angular positions of each of the sleeves 33 and the sleeves 39. By simultaneously rotating the worm wheels 37 and 38 in the same direction and at the same speed, the eccentrics 30 or 31 will be revolved in a circle of constant diameter, that is, with constant eccentricity, and the table will be given its planetary or operative movement.

In order to rotate the eccentric sleeves 33 and 39 constantly so that there will be no angular change between the sleeves, worms 40 and 41 are provided in engagement with the worm wheels 37 and 38 on each of the compound eccentrics. One pair of the worms (for driving the sleeves 39) is on a driving shaft 42 and the other pair of worms (for driving the sleeves 33) is driven therefrom through intermediate gearing presently to be described. Normally and during operative rotation of the driving shaft 42 an intermediate gearing rotates the sleeves 33 and 39 at identical speeds.

In order to vary the eccentricity of the eccentrics 30 and 31 relative to their axes of rotation to vary the planetary movement of the table, a differential driving mechanism 44 is interposed in the driving mechanism for shaft 45 carrying the worms 41 so that the planetary movement of the table 11 may be varied while the machine is in operation. This differential mechanism 44 is clearly shown in Fig. 1 and comprises two opposed bevel gears 46 and 47 within a rotatable housing 48; one of the bevel gears 46 is driven by the main driving shaft 42 and the other gear 47 is directly attached to one of the driving gears 49 for the second shaft 45. Meshing with these bevel gears 46 and 47 are bevel pinions 50 rotatably mounted in the rotatable housing 48 and having a worm wheel 51 on its periphery. If there is no rotation of this housing 48 and worm wheel 51, the bevel gears 46 and 47 are rotated at the same speed in opposite directions and the two shafts 42 and 45 are constantly rotated at identical speeds. Gear 49 on bevel gear 47 meshes with an idler or intermediate gear 53 which is in mesh with a gear 54 directly keyed to shaft 45. As the gears 49 and 54 have equal numbers of teeth the shaft 45 will rotate at the same speed as the gear 49 and consequently at the same speed as driving shaft 42. By angularly adjusting the position of the housing 48, the second bevel gear 47 will be rotated relative to the first bevel gear 46 and thus, through the driving gears 49, 53 and 54, the lower worm wheel 38 will be angularly advanced relative to worm wheel 37. This angularly advances the sleeve 33 relative to the eccentric

sleeve 39 of each of the compound eccentrics and thus varies the position of the eccentrics 30 and 31 on their upper ends.

Heretofore in machines of this type, such as shown in the patent to Grow et al. 1,241,964, the two eccentrics for actuating the table in its planetary paths were mounted at opposite ends of the forward portion of the table, closely adjacent to opposite ends of the engine cylinder body being ground. This necessitated highly accurate machining and precise identity of eccentricity and angular relationship of the two eccentrics to avoid variations in diameters of the bores of the cylinders at one end compared to those at the other end and to function smoothly. The present invention comprises an improved arrangement over this construction by locating the eccentrics in such a manner that a lesser degree of accurate machining is permitted and identity of eccentricity of the two compound eccentrics has a lesser effect upon the ultimate identity or uniformity of the bores which are ground.

It will be seen in Fig. 3 that one of the eccentrics 30 is positioned approximately in the center of the forward end of the table 11 and substantially at the mid portion of the engine cylinder body W. The second eccentric 31 is mounted in the rearward extension 12 of the table 11 and at a distance remote from the engine cylinder body W. It will therefore be seen that the diameters of the bores being ground in the cylinder body W will be governed primarily by the eccentricity of the front eccentric 30 and that the function of the second eccentric 31 is to give the table a correct planetary path. Also by mounting the second eccentric 31 on the table extension 12 in rear of the engine cylinder body W, it may engage a sliding block 35 in the table 11 mounted so that it may adjust itself along a line connecting the two eccentrics 30 and 31. This mounting for the rear eccentric 31 therefore permits simple machining and eliminates the necessity of the openings in the table being accurately bored for the eccentrics, as there is no possibility of any binding action taking place.

To adjust the eccentricity of the eccentrics 30 and 31 simultaneously to compensate for wearing away of the wheel or to adjust the mechanism for a different diameter of bore, manual means are provided for rotating the housing 48. A worm 60 in mesh with worm wheel 51 on the housing 48 is provided on a laterally extending shaft 61. On this shaft 61 is a bevel gear 62 in mesh with a corresponding gear 63 on a forwardly extending shaft 64. A hand wheel 65 on the forward end of this shaft 64, which is preferably provided with graduations 66, permits accurate adjustments of the housing 48 and therefore of the eccentricity of the eccentrics 30 and 31.

What I claim is:

1. A machine for simultaneously grinding the bores of a multiple cylinder engine having its cylinders disposed in a straight line comprising in combination, a base, a table for supporting the work to be ground, a plurality of rotatable abrasive wheels, means for relatively moving the wheels and table to engage the wheels along the length of the bores being ground, and eccentrics engaging the table, one of said eccentrics being positioned at the mid portion of the cylinder body, whereby the table may be actuated in a planetary path of predetermined radius.

2. A machine for simultaneously grinding the bores of a multiple cylinder engine having its cylinders disposed in a straight line comprising in combination, a base, a table for supporting the work to be ground, a plurality of rotatable abrasive wheels, means for relatively moving the wheels and table to engage the wheels along the length of the bores being ground, adjustable eccentrics engaging the table, one of said eccentrics being positioned at the mid portion of the cylinder body, whereby the table may be actuated in a planetary path of predetermined radius, and means to adjust the eccentrics during operation.

3. A machine for simultaneously grinding the bores of a multiple cylinder engine comprising in combination, a base, a table for supporting the work to be ground, a plurality of rotatable abrasive wheels, means to traverse the wheels to engage them with the bores being ground, variable throw eccentrics engaging the table, one of said eccentrics being positioned adjacent the mid portion of the cylinder body being ground, and the other eccentric spaced therefrom in symmetrical relation to the end bores of the cylinder body, and means to simultaneously rotate said eccentrics.

4. A machine for simultaneously grinding the bores of a multiple cylinder engine having its cylinders disposed in a straight line comprising in combination, a base, a table for supporting the work to be ground, a plurality of rotatable abrasive wheels, means to traverse the wheels to engage them with the bores being ground, and variable throw eccentrics engaging the table, one of said eccentrics being positioned adjacent a mid-portion of the work being ground, and the other eccentric spaced therefrom in a direction normal to the line of the cylinders.

5. A machine for simultaneously grinding the bores of a multiple cylinder engine comprising in combination, a base, a table for supporting the work to be ground, a plurality of rotatable abrasive wheels, means to traverse the wheels to engage them with the bores being ground, a rotatable eccentric in engagement with the table, a supplementary eccentric rotatable within the base and slidably engaging the table whereby rotation of

said eccentrics will cause movement of said table in a planetary path, and means to adjust the eccentricity of said eccentrics.

6. A machine for simultaneously grinding the bores of a multiple cylinder engine comprising in combination, a base, a table for supporting the work to be ground, a plurality of rotatable abrasive wheels, means to traverse the wheels to engage them with the bores being ground, a rotatable eccentric in engagement with the table, a supplementary eccentric slideable relative to the table in a direction normal to the line of cylinders being ground, whereby rotation of said eccentrics will cause movement of said table in a planetary path, and means to adjust the eccentricity of said eccentrics during operation.

7. A machine for simultaneously grinding the bores of a multiple cylinder engine comprising in combination, a base, a table for supporting the work to be ground, a plurality of rotatable abrasive wheels, means for relatively moving the wheels and table to engage the wheels along the length of the bores being ground, an adjustable eccentric engaging the table adjacent the mid-portion of the work being ground, a second adjustable eccentric spaced therefrom and slideably engaging the table, means to simultaneously rotate said eccentrics, and means to simultaneously adjust the eccentricity of said eccentrics.

8. A machine for simultaneously grinding

the bores of a multiple cylinder engine comprising in combination, a base, a table for supporting the work to be ground, a plurality of rotatable abrasive wheels, means for relatively moving the wheels and table to engage the wheels along the length of the bores being ground, an eccentric engaging the table in a circular opening therein, a second eccentric spaced from said first eccentric and slideably engaging the table within an elongated opening therein extending in a direction normal to the cylinders being ground, and means to simultaneously rotate said eccentrics.

9. A machine for simultaneously grinding the bores of a multiple cylinder engine comprising in combination, a base, a table for supporting the work to be ground, a plurality of rotatable abrasive wheels, means for relatively moving the wheels and table to engage the wheels along the length of the bores being ground, an adjustable eccentric engaging the table in a circular opening therein, a second adjustable eccentric slideably engaging the table within an elongated opening therein extending in a direction normal to the cylinders being ground, means to simultaneously rotate said eccentrics, and means to simultaneously adjust the eccentricity of said eccentrics.

In testimony whereof, I hereto affix my signature.

CARROLL KNOWLES.
